UNITED STATES PATENT OFFICE.

WILLIAM T. S. BROWN, OF EAST POINT, GEORGIA.

KNOCKDOWN CONTAINER.

Application filed May 7, 1921. Serial No. 467,623.

To all whom it may concern:

Be it known that I, WILLIAM T. S. BROWN, a citizen of the United States, residing at East Point, in the county of Fulton and State of Georgia, have invented certain new and useful Improvements in Knockdown Containers, of which the following is a specification, reference being had therein to the accompanying drawings.

10 The invention relates to containers of the type of which the parts are formed in such manner that they may be assembled and disassembled.

It is an object of the invention to provide 15 a crate or box of that kind that is adapted to be made in various sizes ranging from those of small to those of large capacity.

Another object of the invention is so to 20 form and proportion the parts that they may be easily assembled and disassembled into either a container or a compact package for return shipment or storage.

A further object of the invention is so 25 to arrange the parts that they may be assembled and disassembled without injury thereto, in order that they may remain long in condition for repeated use and expense of providing a new container for every 30 shipment or other purpose thereby avoided.

35 The invention, moreover, provides formation and arrangement of parts that permit them to be held together, both as a container and as a package, by a small number of fasteners, which are arranged so that they serve to maintain the parts together both in container and package assembly.

40 While the invention is exemplified herein as applied to a wooden container, it also may be applied to containers of metal or other material.

When considered in connection with the 45 description herein, the characteristics of the invention will be apparent from the accompanying drawings, forming part hereof, wherein embodiments of the invention in a crate are disclosed, for purposes of illustration.

50 Although the disclosures herein exemplify what now are considered to be preferable embodiments of the invention, it is to be understood that it is not the intention to be limited necessarily thereto in interpretation of the claims, as modifications and adaptations within the limits of the claims 55 can be made without departing from the nature of the invention.

Like reference-characters refer to corresponding parts in the views of the drawings, of which—

Fig. 1 is a view of the crate in assembled condition;

Fig. 2 is an outside view of one of the members constituting the top and bottom;

Fig. 3 is an inside view of one of the end members;

Fig. 4 is an elevation of the partition;

Fig. 5 is a view of battens of alternative form in open position;

Fig. 6 is a view thereof in closed position;

Fig. 7 is a view, partly in section, of the 70 parts in package form;

Fig. 8 is a view of a fastener; and

Fig. 9 is a section on the line 9—9, Fig. 1.

Having more particular reference to the drawings, A designates end members, B 75 side members, C top and bottom members, and D a partition.

As shown, the walls of members A, B, and C are formed of separated slats 9, but they also may be formed of abutting material or 80 each wall of a single piece; and the partition is shown as a single piece of wooden material. Any suitable material may be used, however, for the walls of the members and partition, the character thereof being 85 governed by the size of the container, the uses to which it is to be put, and availability of material.

The members and partition preferably 90 are rectangular in plan, and members that are positioned oppositely in the container are substantially identical, in order that they may be used interchangeably.

Each end member A has battens 10 constituting abutments secured on the inner 95 side of its wall along the edge portions.

Each side member B has a batten 11 constituting an abutment near each end, the batten being located so that the end portion of the wall projects therebeyond sufficiently to seat against the inner side of a batten on an end member and to permit the side and end battens to be brought into abutment.

Each member C, either of which may be the top or bottom in the assembled container, has at each end a batten 12 constituting an abutment located in a position corresponding to the battens of the side members and arranged to be brought into abutment with a batten of the end member with a projecting end portion of its wall resting against the inner side of the latter batten.

The walls of the side and top and bottom members have openings or seats arranged to receive headed retaining members extending from the edges of the partition D, whereby 5 the latter is held in place. Preferably the retaining members are screws 13. The seats preferably are openings 14 large enough to permit the heads of the screws to be passed therethrough and narrower bevel-edge slots 10 15 extending therefrom and arranged to take the shanks of the screws and to have their bevel engage under the heads. It is of advantage to have the slots in the sides of the container extend downwardly from 15 the larger openings of the seats, in order that, after the heads of the retaining members 13 are passed into the openings, they may be moved into the slots by pressing the partition downwardly.

20 The side battens 10 and the walls of the end members and the battens 11 of the side members are formed with holes or passageways 16, which are positioned so that those of abutting or opposite battens will be 25 aligned both when the parts are assembled as a container and a package. The walls of the end members adjacent to their holes or passageways are formed with seats 17.

The holes or passageways and seats are 30 arranged to receive, respectively, the threaded shanks 18 and hook-heads 19 of fastening bolts or members.

When the parts are assembled as a container, the bolts extend through aligned holes 35 in abutting end and side battens and the ends of their hooks are disposed in the seats 17. The battens are drawn and held closely together by nuts 20, which bear against the inner sides of the side battens, the hook-heads in the seats preventing the bolts from turning while the nuts are being turned.

The number of bolts it is necessary to use in a container depend upon its size and the purposes for which it is to be used. 45 With containers of small or medium size and with larger ones to hold comparatively light articles or material, four bolts usually are sufficient, one being disposed through each pair of abutting side and end battens 50 midway between the top and bottom, as shown by the drawings. However, other numbers of bolts may be used at each of the four side ends or corners of the container. For example, one may be located 55 near the top and the other near the bottom of each corner. Holes in the battens, for the number of bolts to be used, are placed uniformly, so that, no matter which end of either side is placed with its batten in abut- 60 ment with either side batten of an end member, the holes therein are aligned.

The abutting sides of end and side battens may be straight as shown by the views other than Figs. 5 and 6, or interlocking 65 battens of a form such as shown by those

figures may be used. In the latter case, one of the battens, for example a side batten 11^a, decreases in thickness from each end to its longitudinal center and from the outer to the inner edge, and the abutting batten 70 10^a on the end member is shaped reversely on its abutting side. When two such battens are brought together, the end batten wedges against the side batten and against the wall of the side member B and a reliable and firm joint thereby is afforded.

75 The parts may be assembled to form a container in any suitable manner. One method that may be followed with advantage is to place ends of the two side members into engagement with side battens of an end member and with those battens in abutment with those of the side members. Bolts then are placed in the holes of those battens, with the ends of their hooks disposed in the seats therefor, after which the nuts are turned loosely onto the bolts. The member C that is to constitute the bottom then is placed with the projecting end portion of its wall at one end in abutment with the bottom batten of the end member and with that batten in abutment with the adjacent batten of the member C. Thereupon, the other end member is brought into similar 85 association with the bottom and sides, bolts are passed into holes at the last-fitted end, and the nuts of both sets of bolts are tightened. If the partition is not to be used in the container, the latter now is ready to receive articles or material.

90 In the event the partition is to be used, the retaining members 13 on the side edges thereof are brought into engagement with the seats in the side members either before or after the side members are associated with one of the end members, the bottom member has its seats engaged by the retaining members on the bottom edge of the partition by longitudinal movement, and the other end member then is associated with the side and bottom members as previously described.

95 After the container has been filled, the bolts at each end are loosened, an end of the member C that is to constitute the top is slipped under the top batten of one of the end members, the upper portions of the end members are sprung outwardly (that being permitted by the loosened bolts), and the end of the top member that then is free is pressed downwardly by the adjacent top batten of the other end member and moved thereunder. The seats in the wall of the members C are arranged so that their 100 larger portions receive the heads of the retaining members 13 on the upper edge of the partition prior to or at about the time an end of the top is passed under a batten of an end member, and the narrowed portions of the seats extend longitudinally so that 105 110 115 120 125 130

they move into engagement with the retaining members during the movement incident to bringing the end of the top member under the batten of the end member.

5 After both ends of the top are in position under the top battens of the end members, the nuts of the bolts are tightened, all abutting battens are brought tightly together, and the entire structure is held by the bolts
10 firmly associated as a completed article.

The battens of the end members engage the outer sides of the end portions of the side, top, and bottom members, and prevent outward displacement thereof. The ends of
15 the battens on the side members project over the ends of the battens on the top and bottom members, the latter battens at their ends rest on the edges of the walls of the side members, and the end edges of the side, top, and bottom members and the battens thereof are in contact, respectively, with the walls and battens of the end members, whereby inward collapse of the walls of the container is prevented. Such stresses as tend toward
25 outward and inward displacements of this character are sustained without imposition of strains on the holding-bolts, which only are required by longitudinal effort to prevent outward displacement of the end
30 members.

When a partition is in the container, and connected with the sides, top, and bottom as described, it acts as a strengthening means between the ends to prevent bending of the
35 walls both inwardly and outwardly.

The top of the container may be removed to permit discharge of the contents by reversal of the order of operations hereinbefore described for its placement, that is, 40 the bolts are loosened, the upper portions of the end members are sprung outwardly, one end of the top is disengaged from the batten that has been holding it, and the top then is drawn from under the other end batten and
45 from engagement with the upper partition-holding members. After discharge of the contents, the bolts again are tightened if the container is to be used immediately as such; or the remaining parts may be disassembled
50 upon removal of the nuts and withdrawal of the bolts.

When the parts are to be assembled into compact package form for shipment or storage, the partition is laid on the inner side 55 of one of the end members between the battens thereof, one of the side or top or bottom members is placed with its battens down on that end member across the battens thereof that do not have bolt-holes, the other side, 60 and top, and bottom members are placed thereon with the battens of two of them nested and with the battens of the top one uppermost, and then the other end member is laid on and between the battens of the
65 member last previously placed. The end

members are placed so that the bolt-holes thereof are alined. Two of the bolts then are disposed in each pair of alined holes with their hooks in engagement, and the nuts are tightened. The parts are thus held together
70 by the bolts in a compact package from which they are not apt to be displaced during shipment or other handling.

It will be seen that the bolts serve to hold the parts together both when assembled as
75 a container and in package form, for the first purpose the bolts being passed into the holes from the outer sides of the end members, and for the latter purpose from the inner sides thereof.
80

Having thus described my invention, what I claim as new, and desire to secure by Letters Patent, is—

1. As cooperable parts of a knockdown container, end members having abutments
85 on the inner sides at the edge portions thereof; members arranged to be disposed between said end members with their end portions against the inner sides of said abutments and having abutments arranged to
90 abut those of the end members, there being holes in some of said abutments arranged to be alined; and bolts having hooks, each of said bolts being arranged to be disposed in alined abutment holes when the parts are
95 assembled as a container whereby to hold the parts together, and each pair of said bolts being arranged to be disposed in holes of said end members with their hooks in engagement whereby to maintain the parts in
100 package form.

2. A package of container parts comprising end members having alined holes therein, between said members parts arranged to form other portions of the container, and bolts having hooks constituting heads, each pair of said bolts with their
105 hooks in engagement being disposed in alined holes in said end members.

3. As cooperable parts of a knockdown container, end members having battens on the inner sides at the edge portions thereof, two of oppositely-disposed battens having holes therethrough, members arranged to form other parts of the container and to
110 have their end portions seat against the inner sides of said battens and having battens arranged to abut them, two of said latter battens having holes arranged to be alined with those of the end members, one of said
115 battens decreasing in thickness from its ends to its longitudinal center and from its outer to its inner side, and another of said battens being reversely shaped on its abutting side, and fasteners arranged to be disposed in said holes when alined whereby to hold the parts together.
120

In testimony whereof I affix my signature.

WILLIAM T. S. BROWN.
